UNITED STATES PATENT OFFICE.

HERBERT H. PATTEE, OF PHILADELPHIA, PENNSYLVANIA.

BICYCLE.

SPECIFICATION forming part of Letters Patent No. 636,921, dated November 14, 1899.

Application filed March 17, 1898. Serial No. 674,271. (No model.)

To all whom it may concern:

Be it known that I, HERBERT H. PATTEE, a citizen of the United States, residing at Philadelphia, in the county of Philadelphia and 5 State of Pennsylvania, have invented certain new and useful Improvements in Bicycles; and I do hereby declare the following to be a full, clear, and exact description of the invention, such as will enable others skilled in 10 the art to which it appertains to make and use the same.

This invention relates to an improvement in that class of bicycles having self-contained pumps, the object being to provide a simple 15 and efficient pump at small cost which may be practically a part of the machine, and hence capable of being carried and operated with great ease and facility, while not sensibly adding to the weight; and the invention 20 therefore consists in the construction, arrangement, and combination of parts, substantially as will be hereinafter described and claimed.

In the annexed drawings, illustrating my 25 invention, Figure 1 is a perspective view of the front part of a bicycle provided with my improved pump. Fig. 2 is a longitudinal sectional detail showing the various parts of the pump. Fig. 3 is a modification of the valve 30 at the lower end of the handle-stem or its extension.

Like letters of reference designate like parts throughout all the different figures of the drawings.

A denotes the front part of a bicycle-frame, 35 to which part the arms *a a* are attached. B denotes the handle-bar, having the handles *b b*. B' is the crown of the front fork, which may be of any suitable construction, and C indicates the front wheel, provided with the 40 usual expandible tire. These various parts are shown here merely by way of example to illustrate the practical application of my invention to a machine.

The crown-piece B' is formed integral with 45 or otherwise connected to the upwardly-extending crown-tube D, within which tube D is adjustably fitted the hollow handle-stem E, which projects downwardly from the handle-bar B. The upper end of the crown-tube D 50 is preferably provided with an inset-packing *d*, that surrounds the handle-stem E and makes a tight joint at that point. The handle-stem

E is elongated or is preferably provided with a tubular extension E', of brass or other metal, securely fastened thereto and having the same 55 internal diameter as the handle-stem E, so that the said handle-stem and its extension may serve as a pump-barrel to contain an air-compressing piston. The crown-tube D swivels within the frame-socket A in the ordinary 60 way. Means are provided, as usual, to prevent the handle-stem, crown-tube, and front part of the frame from rotating relatively to each other and to otherwise secure them to each other detachably. 65

The piston within the handle-stem E consists, essentially, of a collapsible leather washer G, on the under face of which is a metal disk or washer *g*, through which passes a screw *g'*, which secures the washers *g* and 70 *G* to the flat lower end F' of the piston-rod F. This rod passes upwardly through the handle-stem E and through openings at *f'* and *f'* in the handle-bar B, said openings being large enough to allow the piston-rod F to play 75 loosely through them and so that air may be supplied through them to the pump. The length of the handle-stem and its extension E' permits the compressing-piston to have a sufficiently long stroke to do its work 80 efficiently. On the upper and outer end of the piston-rod F is a disk or handle *f*, that is of any desired shape, by means of which the rod is grasped to operate the pump-piston.

In order to effect a successful working of 85 the apparatus and prevent leakage, it becomes necessary to secure an absolutely tight joint at the lower end of the hollow barrel E E', between said end and the contiguous wall of the surrounding crown-tube D. 90 Hence I first attach to the lower end of said handle-stem extension-tube E' a screw-cap and spindle H, of metal, which screws upon the externally-threaded lower end of the tube E'. A vertical screw I, having a longitudinal 95 central passage through the same, enters the lower end of the tube E', where it is furnished with a nut I', which clamps a washer *i* tightly between itself and the screw-cap H, and in this way the screw I is firmly fastened to the 100 cap H. Below cap H is a cup-washer J, and below it is a metal washer *j*. Below washer *j* is a short spacing-sleeve K, then another washer *k*, preferably of greater diameter than

washer *j*, then another leather cup-washer *L*, and then a metal washer *l*. The screw *I* passes through the several parts just mentioned—viz., washer *l*, cup-washer *L*, washer *k*, sleeve 5 *K*, washer *j*, and cup-washer *J*—and clamps them all tightly together and to the screw-cap *H*, the head *I*² of screw *I* fitting closely against the lower washer *l*, as shown. Within the screw-head *I*² is a chamber having a conical 10 valve-seat and containing a conical valve *M*, whose stem or spindle *m* extends into the longitudinal passage in the screw *I* and acts as a guide for the valve. A screw-plug *M'* is used to close a central opening in the screw-head *I*², whereby access can be had to the said valve-chamber, and the latter is provided with a lateral outlet or escape port *M*² for the compressed air. Thus the two cup-washers *J* and *L*, expanding, as they do, against 15 the interior wall of the crown-tube *D*, form an absolutely tight joint that prevents any air from escaping between the adjoining walls of the handle-stem *E* *E'* and the crown-tube, and at the same time the bored screw *I* furnishes a passage through which the 20 compressed air passes out from below the compressing-piston and into the lower end of the crown-tube *D*. (See Fig. 2.)

The crown-piece *B'* generally has an opening below the crown-tube, which opening is the lower end of said tube. I fill this opening with a block of wood or metal *N*, which is secured in place by means of a cement-filled groove or by pins or other efficient 30 means. In order to make a tight joint, a cup-washer *O* is placed contiguous to the block *N*, within the crown-tube *D*, and on this is a metal disk *o*, through which passes a headed screw *P*, having a longitudinally-bored shank, 35 the shank passing through a central opening in the block *N*. In this way a tight joint is made at the lower end of the crown-tube *D*. The lower side of the block *N* is entered by a curved screw-threaded pipe *p*, to which a 40 flexible pipe *p'* may be fastened for conveying air to inflate the tire.

The operation of my improved pump will be manifest from the foregoing description of the construction and arrangement of parts. 50 A few reciprocations of the piston by manipulating the conveniently-located handle *f* will be sufficient to compress enough air to fill a tire. As the air is compressed it fills the chamber below the lower end of handle-tube *E'* in the crown-tube *D*, as I have explained, from whence it is discharged through the channels described to the tire or other place of use. It will be evident that as the air is compressed in advance of the descending piston *G* it will enter the passage in screw *I* and pass through the valve *M* and out through slot *M*² into the lower end of crown-tube *D* and thence through the passages described into the tire which is to be inflated. As the 60 piston rises again the valve *M* will close and prevent the air which has been previously compressed from escaping. This operation

will continue until the tire has been fully inflated.

In Fig. 3 I have shown a modification in 70 the arrangement and construction of the bored screw and its internal valve that are placed at the lower end of the tube *E'*. Instead of screw *I*, I employ a screw *I'*, having therein a valve *M*⁴, and the head *I*⁵ of screw 75 *I'* has no central screw, as *M'* in Fig. 2. The valve *M*⁴ has a bent end *m*² on the upper end of its rod, which keeps the valve *M*⁴ from falling out of screw *I'*. The operation of valve *M*⁴ is substantially the same as that of valve *M*. 80

Numerous changes in the exact combination and construction may be made without departing from the invention.

Having thus described my invention, what I claim as new, and desire to secure by Letters 85 Patent, is—

1. In a bicycle, the combination with the crown-tube, and the hollow handle-stem therein, of means at its lower end for making a tight joint between the two parts and preventing 90 the escape of air, said means consisting of a cap secured to the lower end of the handle-stem, a cup-washer, a metal disk, and a hollow securing-screw, having an aperture in its head and whose shank is centrally mounted 95 in the cap, a valve mounted within the hollow of the screw, and adapted to normally close the aperture in the head thereof, a compressing-piston within the handle-stem, having a rod provided with an external handle, 100 substantially as described.

2. In a bicycle, the combination with the crown and crown-tube, of means for closing the lower end of said tube consisting of an inserted, passaged block, a cup-washer, a metal disk, a bored screw for fastening the parts together and an air-outlet tube; the handle-stem within the crown-tube, said stem serving as a pump-barrel, and provided at its lower end with packing means for making a 105 tight joint between the handle-stem and crown-tube, said means consisting of a cap secured to the lower end of the handle-stem, a cup-washer, a metal disk, and a hollow securing-screw having an aperture in its head 110 and whose shank is centrally mounted in the cap, and a valve mounted within the hollow of the screw and adapted to normally close the aperture in the head thereof; and a compressing-piston within the handle-stem having a rod whereby it is operated, substantially as described.

3. The combination with the outer casing-tube *D* and its contained pump-barrel *E* *E'*, of a piston-rod, a washered piston, a washered screw-cap *H* inserted in the lower end of said pump-barrel, a hollow screw *I* passing vertically through the cap *H* and its washers and clamping them in position, said screw *I* having a chambered head *I*² forming a valve-chamber with an interior conical valve-seat, a lateral opening *M*² in said valve-chamber, a conical valve *M* therein whose stem or spindle *m* reciprocates within the hollow spindle 125 130

of the screw I, a screw-plug M' closing the central opening in the screw-head; substantially as described.

4. The combination, constituting a bicycle-pump, of a bicycle-frame carrying a front fork and crown-piece and crown-tube supported thereby, of a pump-barrel sleeved within the crown-tube, a piston and rod therein, valve devices at the lower end of the pump-barrel through which compressed air is discharged, said devices consisting of a cap secured to the lower end of the handle-stem, a cup-washer, a metal disk, and a hollow securing-screw, having an aperture in its head and whose shank is centrally mounted in the cap, a valve mounted within the hollow of the

screw and adapted to normally close the aperture in the head thereof; and devices consisting of a cup-washer O with its metal disk o at lower end of crown-tube, a block N inserted 20 in a vertical opening in the crown-piece B', a longitudinally-bored screw passing through a central opening in the block N, and a nozzle p secured in said opening; said parts being constructed, combined and operating substantially as set forth. 25

In testimony whereof I affix my signature in presence of two witnesses.
